BARBECUE CHICKEN HOLDER

Lawrence M. Kissner and Robert Claybin, both of 1215
S. Stanford Ave., Los Angeles, Calif. 90021

Filed Dec. 26, 1967, Ser. No. 9,911

Term of patent 14 years

(Cl. D81—10)

We claim:

The ornamental design for a barbecue chicken holder, substantially as shown.
